(57) **CLAIM**

The ornamental design for an ultra light glove, as shown and described.

DESCRIPTION

FIG. 1 is a top plan view of an ultra light glove;
FIG. 2 is a left side elevational view of the design of FIG. 1;
FIG. 3 is a bottom plan view of the design of FIGS. 1-2;
FIG. 4 is a right side elevational view of the design of FIGS. 1-3; and,

FIG. 5 is a front elevational view of the glove design of FIGS. 1-4.

The indicia shown in broken lines on the cuff of the glove in FIGS. 1 and 4 is for the purpose of illustrating environmental subject matter that forms no part of the claimed design.
